CLAIM

I claim the ornamental design for a chicken coup, as shown and described.

DESCRIPTION

FIG. 1 is a perspective view of a chicken coup, showing my new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof; and,

FIG. 6 is a bottom plan view thereof.

The broken lines in the drawings illustrate environmental matter that forms no part of the claimed design.
